J. RONCAGLIONE.

TRAIN PIPE COUPLING FOR RAILROAD CARS.

APPLICATION FILED FEB. 9, 1915.

1,194,074.

Patented Aug. 8, 1916.

UNITED STATES PATENT OFFICE.

JOSEPH RONCAGLIONE, OF CARLISLE, WEST VIRGINIA.

TRAIN-PIPE COUPLING FOR RAILROAD-CARS.

1,194,074.

Specification of Letters Patent. Patented Aug. 8, 1916.

Application filed February 9, 1915. Serial No. 7,031.

To all whom it may concern:

Be it known that I, JOSEPH RONCAGLIONE, a citizen of the United States, residing at Carlisle, in the county of Fayette and State of West Virginia, have invented certain new and useful Improvements in Train-Pipe Couplings for Railroad-Cars; and I do hereby declare the following to be a full, clear, and exact description of the invention, such as will enable others skilled in the art to which it appertains to make and use the same.

This invention relates to new and useful improvements in train pipe couplings for railroad cars, and has for its principal object to provide a device which will automatically connect the train pipes thus throwing the air brake system into and out of operation upon movement of one of the cars in relation to the other.

A still further object of the invention is to provide a novel form of air tight coupler which will effectively hold the air to prevent the same from leaking off and permitting the brakes of the system to be set.

With these and other objects in view, the invention consists in the novel combination and arrangement of parts which will be fully set forth in the following specification and accompanying drawings, in which—

Figure 1 is a view of the coupling showing the same partly in section, and Fig. 2 is an enlarged fragmentary sectional view of the flange and flared portion.

Referring now to the drawing by characters of reference, the numeral 1 designates as an entirety, a railroad car of the ordinary construction, while the numeral 2 designates the adjacent car. Each of these cars carries the coupling bar 3 having formed at its free end the coupling head 4. The usual train pipe is designated generally 5 and is carried by each of the cars and this train pipe is provided at each end with a suitable valve 6 for an obvious purpose.

Secured to the valves 6 are the pipe couplers designated generally 7, each of which comprises a U-shaped body, which is formed with the arms 8 and 9 respectively. These arms 8 and 9 are connected by the bight portion 10 and this bight portion is formed intermediate its ends with the stem 11 which carries the universal connection 11' which is connected to the valves 6. The arms 8 and 9 of the U-shaped body are provided

with the inturned flanges 12 which are designed to act as stops for the inner slidable members which will be more fully herein-after described. Slidable in each of the arms 8 are the slidable members 13 which are provided with longitudinal bores and with the end closures 14 which have formed therein the apertures 15. A suitable coil spring 16 bears against each of the end plates 14 and is designed to force the slidable members 13 outwardly. The opposite end of the coil spring bears against the web or spider 17 which is formed interiorly of the arm 8 and is designed to hold the spring 16 under compression, to limit the inward movement thereof. The slidable members 13 hereinbefore referred to are each provided near the end opposite the closure 14 with the flange 18, the outer end of which is tapered and inclined as clearly shown in Fig. 2. A suitable gasket or washer 19 is arranged to engage the inclined face of the flange 18 to form an air tight joint, the use of which will be more fully herein-after described. A suitable washer surrounds each of the slidable members near its closed end and forms an air tight joint between the slidable member and its respective arm.

Slidable in the arms 9 and designed to co-operate with the slidable members 13 are suitable sleeves 20, each of which is closed at one end, as at 21 and provided with the apertures 22 for the free passage of air therethrough. This closure 21 like the closure 14 of the sleeve 13 is designed to form an abutment for the spring 23, the inner end of which bears against the spider 24, and thus holds the spring under compression in such position that the sleeve 20 projects beyond the end of the arm 9 of the coupler. The projecting end of the sleeve 20 flares outwardly as at 25 and the angle of the flare conforms to the inclination of the outer face of the flange 18. A suitable gasket 26 fits within the flaring portion and co-operates with the gasket on the flange 18 in forming an air tight joint between the co-operating arms of the couplers 7. The closed end of the sleeve 20 is provided with a suitable packing to form an air tight joint between the arm 9 and itself.

It will be apparent from the foregoing that in use, when it is desired to couple two cars, the same are brought together in the usual manner and in such a way that the flared end of the sleeve 20 acts as a guide so

that the flanged end of the slidable member 13 will easily slide into the arm of the adjacent coupler. After the slidable member 13 has entered the sleeve 20, the gaskets will 5 engage each other and form an air tight joint which will permit the cars to move slightly with relation to each other and yet prevent any escape of air from the train pipe. It will also be apparent that as soon 10 as the cars move apart, the couplers will disengage and thereby permit the air to escape from the train pipe, thus setting the brakes and bringing the train to a stop.

In order to prevent the springs 16 and 23 15 from forcing their respective slidable members and sleeves entirely out of the arms 8 and 9 there is provided a flange or similar stop member 27 which is designed to engage the flange 12 on the respective arm.

20 While in the foregoing there has been shown and described the preferred embodiment of this invention, it is to be understood that such changes may be made in the combination and arrangement of parts as will 25 fall within the spirit and scope of the appended claims.

What is claimed is:—

1. A train pipe coupler of the character described including a hollow U-shaped body, 30 a sleeve slidable in one arm of said body, a perforated closure plate at the inner end of the sleeve, a spring bearing at one end against the perforated closure plate, a spider within the arm, said spider engaging the 35 free end of the spring limiting the inward movement of the same, said sleeve projecting beyond the end of the arm and flared, lugs formed in said arm to limit the outward movement of said sleeve, a slidable 40 member in the adjacent arm, a perforated closure plate formed at the inner end of the slidable member, said slidable member projecting beyond the end of the adjacent arm and having a tapered flange adjacent its 45 outer end, a spring bearing at one end

against the perforated closure for forcing the sleeve outwardly, a spider to limit the inward movement of said spring, lugs formed in said adjacent arm to limit the outward movement of said slidable member, said 50 flaring portion of the sleeve and the tapering flange of the slidable member adapted to engage a corresponding sleeve and flange on an opposing head of an adjacent car.

2. A train pipe coupler of the character 55 described including a hollow U-shaped body, a sleeve slidable in the arm of the body, a perforated closure plate in the inner end of the sleeve, a spring bearing at one end against and connected to the perforated closure plate, a spider within the arm, said spider connected to the spring for limiting the inward movement of the same, said sleeve having its outer end flared and provided on its interior with a gasket, the 60 outer end of the sleeve projecting beyond the end of the arm, a slidable member in the adjacent arm, a tapered inclined flange adjacent the outer end of the slidable member, a perforated closure plate formed on 65 the inner end of the slidable member, the said slidable member projecting beyond the end of the adjacent arm, a spring bearing against the perforated closure plate and connected thereto to force the sleeve outwardly, a spider to limit the inward movement of the same, and means to limit the outward movement of the sleeve and slidable member, said tapered inclined flange provided with a gasket, said slidable member 70 with its tapered flange and sleeve with its flared portion adapted to form an air tight connection between the sleeve and slidable members of an opposing car head.

In testimony whereof I affix my signature 75 in presence of two witnesses.

JOSEPH RONCAGLIONE.
